UNITED STATES PATENT OFFICE.

JOHN M. LARSH, OF INDIANAPOLIS, INDIANA, ASSIGNOR OF ONE-HALF TO WILLIAM MODE TAYLOR AND ONE-FOURTH TO ULYSSES GRANT SMITH, BOTH OF INDIANAPOLIS, INDIANA.

ROAD-MACHINE EXCAVATING AND STEERING MECHANISM.

Original application filed January 4, 1926, Serial No. 79,245. Divided and this application filed August 11, 1926. Serial No. 128,531.

This invention relates to mold boards for road machines, and the mechanism for steering the machine while the mold board is in use, and is a division of my application for a patent on a road making machine filed January 4, 1926, Serial No. 79,245.

One object of this invention is to provide a double suspension for the mold board from a two-part V-shaped draw-bar connected 10 with the front of the machine by a single hinge and having a rear-end means for laterally adjusting that end of the draw-bar to correspondingly shift the mold-board.

A further object is to provide means, operated from the rear platform, for independently raising or lowering each member of the two-part draw-bar in order, thereby, to raise or lower the corresponding end of the mold-board.

Another object is to provide a resilient support from the body-frame for the mold-board, which will assist in and thereby reduce the labor of raising the mold-board off of the ground, as when it is desired to

turn the road machine or haul it when not scraping the road, and which will assist in holding the mold-board against the roadway while the road machine is at work.

I accomplish the above principal objects and other minor ones that will hereinafter appear, by the mechanism illustrated in the accompanying drawings, in which—

Fig. 1, is a top plan view of so much of a road machine as is essential for the illustration of my invention, with my improvement in operative assembly therewith;

Fig. 2, is a side elevation, with the rear wheels, and parts unessential to a clear understanding, removed, but with my invention shown as in Fig. 1;

Fig. 3, is a detail in vertical section, on the line 3—3 of Fig. 4, of the connection between the rear axle and draw-bar of the machine;

Fig. 4, is an elevation and vertical section of same from the line 4—4 of Fig. 3;

Fig. 5, is a detail of the mold board raising and lowering mechanism; and

Fig. 6, is a view in cross section on the line 6—6, of the Fig. 5; Fig. 7, a cross section on the line 7—7 of Fig. 1, and Fig. 8, is a detail in section on the line 8—8 of Fig. 7.

Referring to Figs. 1 and 2, 1 is the body

frame of the machine, 2, 2, are the front road wheels, and 3, 3, are the rear road wheels. Between the front and rear wheels is the mold board 4. Depending from the body frame is a segmental rack 5, with which a pinion 6 engages to move the rack and rock the frame. The body frame is 60 rockably hinged on a front end middle shaft 200, and a rear middle shaft 201 shown in dotted lines in Fig. 2. The shafts are journaled in suitable cross members of the frame and in adjacent box members from 65 which, diagonal braces 202 at the middle of the machine extend down and are fastened to the draw-bar in front and to the axle in the rear. This rear axle is formed out of two parallel angle bars 12, 12. The wheels 70 2, 2, are mounted on axle stubs which are attached by knuckles 52 with a lever 53 which is pivoted to a front axle 35 that is not skewable relative to the body-frame 1 for steering purposes, but the steering is 75 accomplished by means hereafter to be described.

I will now describe the mechanism by which the front wheels 2, 2, are shifted laterally of the body frame.

A front axle 35 comprises two flat bars turned edge up and separated by a channel bar secured to and between their upper edges, with the channel down. Fixed in this channel is a rack 36, which is engaged 85 by the teeth of a spur gear wheel 37 mounted on a shaft 38. The flat bars of the axle have longitudinal slots 39 for the passage of the shaft and on one projecting end of the shaft a worm wheel 40 is mounted and is 90 driven by a worm 41 on a shaft 42, which carries a bevel wheel 43 that is driven by a pinion 44 on a vertical shaft 45. A bevel wheel 46 on shaft 45 is driven by a pinion 47 on a shaft 48. The latter terminates 95 above the rear axle and is provided with a hand crank 49. The shaft 48 has universal joints 50, 50, to prevent cramping of the shaft which might otherwise be caused by irregularities in road surface over which the 100 machine often travels.

The wheels 2, 2, are mounted on stubs which are connected by vertical pivots in spindles 52, 52, which are supported by bracket extensions from respective vertical 105 arms 53, 53, which are attached to the front

axle 35 by pivots 54, 54. The manner of turning the front wheels for steering the machine will be hereinafter described.

The arms 53, 53, are connected by ball and 5 socket joints 55, 55, at their upper ends, with a horizontal rack bar 6. This rack bar is normally held from longitudinal movement with the axle 35 by a spur gear wheel 57, which engages it. The shaft for the spur 10 gear is journaled in a housing 58, suspended on rollers 59' from the top of the rack bar 56 and is free to move vertically with the bar 56 but is held by vertical frame bars 72 from movement longitudinally of bar 56, 15 with one result, that when the axle 35 is shifted longitudinally, the wheels 2, 2, are tilted because the upper ends of arms 53, 53 are held from corresponding movement by the bar 56 but their lower ends carrying the 20 pivots 54 swing out of plumb with upper ends 55, and bar 56, housing 58 suspended from the bar, gear wheel 57 and associated parts supported by the housing move down closer to axle 35.

25 Thus it is apparent that the front wheels 2, 2, and its axle may be moved longitudinally of the axle by manipulation of hand crank 49, and, also, that the wheels will be automatically tilted.

30 But as this tilt may be too much or too little to conform the wheels with the lateral slope of the road-grade I provide a rectifying means which additionally utilizes the rack-bar 56 and gear 57. The shaft 59, carrying the gear wheel 57 has a gear wheel 60, that is operated by a worm 61' mounted on a shaft 62 journaled in brackets depending from shaft 59 (see Fig. 8) and a bevel wheel 63 on shaft 62 is driven by a bevel pinion 64, on a vertical shaft 65. The shaft 65 has a universal joint 66, and is also in two telescoping sections as shown, to allow for variations in shaft-length and shaft-positions which occur, a bevel wheel 67 at the top of 45 shaft 65 is driven by a bevel pinion 68 on a shaft 69, that extends rearwardly and terminates with a hand crank 70 in convenient reach of the operator on the rear platform 34.

50 The shaft 69 has two universal joints 71, as shown in Fig. 1 to keep the shaft from binding when the machine is on uneven roads. By a proper manipulation of hand crank 70 the rack bar 56 can be moved longitudinally of itself in either direction to change the angular relation of wheels 2, 2, to the road surface and the bar 56 can tilt on the gear wheel as a pivot when the machine is moving over uneven ground, without moving the bar longitudinally.

A draw-bar 71', see Figs. 1, and 2, is attached to vertical angle-bar standards 72. (It is to this draw bar that a second draw bar is connected that carries the mold board, 65 as will be hereinafter described.) Connect-

ed with the front end of draw 71' by a link 73, is a tongue 74, the front end of which is free to swing about link 73, as a hinge, and pivoted under the rear end of steering tongue 74 is a draft tongue 75 the front end 70 of which is attached to a tractor or other draft power (not shown). The weight of tongue 74 is resiliently supported from the body-frame 1 by a spring hitch 76. Slidably mounted in a suitable horizontal opening in tongue 74 is a box 81 through which slides a pair of channel bars 77, 77, having a rack-bar 78 in the channel of the upper one, which rack-bar is in engagement with a spur gear wheel 79. The shaft 80 (see 80 Fig. 1) of the spur gear wheel is suitably journaled in the box 81 on the tongue and carries a worm-wheel 82 which is driven by a worm 83 on the lower end of a vertical shaft 84. The box 81 has a vertical pin 85 180' which passes between the tongue and a guide-bar 151. The shaft 84, as shown in Fig. 2, is in two telescoping members and has a universal joint 85, and the shaft terminates with a bevel wheel 86 that is driven by a bevel pinion 87 on a shaft 88 that extends back to a crank 89 above platform 34. The shaft 88 has the universal joints 90, 90. When the crank 89 is turned the rack-bar 78, by the action of the intervening mechanism above described, is correspondingly moved longitudinally through the tongue, and it is obvious that by suitably connecting the ends of the channel bars 77 with which rack bar 78 is fastened, with the axle studs 100 on which the front wheels 2, 2, are mounted, the latter will be turned in directions to steer the machine. To this end the axle studs are formed with forwardly projecting arms 91, 91, see Fig. 2 and these are connected by link-bars 100, 100, with the respective ends of the channel bars 77. The link-bars preferably comprise vertical joints 101', 101'. The bar 78 and box 81 move longitudinally of the tongue in adjustment required by the 110 swing of the front wheels 2, 2.

To prevent injury to the machine by contact of a front wheel or its hub with a pole or other road obstructions I provide a release in the form of a breakable pin 180 of wood or the like, which will break and allow the contacting members to give way when the strain exceeds the resistance of the pin, and the breakage is repaired by inserting a new pin.

I will now describe the draw-bar construction that takes the main working load and strain of the machine; also the attachment to it of the mold board.

The draw-bar to which the mold board is attached is preferably in two parts 101, 101, the forward ends of which meet and are attached to an eye-bolt 102, which is hinged to a loop fastened to the rear of draw-bar 71', to the front of which the draft tongue 130

of the machine is attached, whereby there is a direct pull on the mold-board-carrying draw-bar irrespective of the rest of the machine. The members 101, 101, diverge rearwardly from the eye-bolt 102, and are connected at a suitable distance by a pivot-block 104. A bar 105 connects the ends of a semi-circular angle-bar 106, and this bar 105 is secured to the block 104 by a pivot-pin 107.

- 10 Fixed to the bar 105, concentrically of pin 107, is a wheel 108 having an annular row of side cogs 109 which are engaged by a cogged wheel 110, on a shaft 111 that extends back under platform 34 and terminates with 15 a foot-wheel 112, the upper portion of which projects far enough through the platform to allow the wheel and shaft to be rotated by foot movement of the operator. A suitable locking mechanism (not shown) may 20 be used if necessary to prevent accidental rotation of the wheel 112.

The ends of the semicircular angle bar 106 turn down and provide the attaching means for a mold board 4, of usual construction, the angular adjustment of which across the machine is secured by the above described mechanism controlled by the foot wheel 112, and a required adjustment so secured is retained by passing a pin 113 through one of a series of hole 114 in the vertical flange of the angle-bar 106. The pin 113 is mounted in brackets 115 depending from the draw bars 101, 101. It is pressed into engagement with the holes in 35 the flange by a spring 116 see Fig 2 and is withdrawn by a foot lever 168 pivoted in the platform 34 and connected with the pin by a cable 117.

Pivoted to the rear ends of both draw bar 40 members 101, 101, is a yoke 118, having a rearwardly extending stem upon which a tube 119 is fastened. Telescoping into the tube from its rear end is a second tube the rear end of which is pivoted to ears integral 45 with a plate 120 see Figs. 3 and 4, which has sliding adjustment on the head of a T-bar 121 which is bolted to the horizontal flange of the front angle bar which comprises a part of the rear axle. The plate has top and bottom hook edges to receive the head of the bar 121 as shown in Fig. 3. The tube adjacent to plate 120, has a universal joint as shown in Fig. 2, or a ball and socket joint as shown in Fig. 3, to afford the necessary 55 adjustments and freedom of movement of parts. The plate 120 is positioned and held by a chain 122 which has its two ends fastened to ears on plate 120 as shown in Figs. 3 and 4, and which passes in a taut condition around the bar 121. It is kept taut by taking up slack due to wear by removing bolt 123 and screwing the threaded bolt 124 into the female link member 125. This avoids twisting the chain, which is further 60 kept in condition by passing around

pulleys 126, 126, at the ends of bar 121 as shown in Figs. 1 and 4.

I will now describe the mechanism for lowering and raising the mold board as a whole or at either end. The weight of the 70 body-frame and parts attached thereto is utilized for forcing the mold-board into the road surface and for holding it there. This weight is applied through mechanism duplicated for each draw-bar member 101, 101, 75 and as they are both alike, a description of one will suffice for both.

This comprises a substantially vertical rack-bar 127, the lower end of which is pivoted to and between a pair of angle-bars 128, 80 128, upon and connecting the rear end of members 101, 101. This connection as shown in Fig. 2, is a universal joint, but it may be a ball-and-socket joint, thereby allowing the toothed upper portion of the rack bar to remain always in mesh with a gear wheel 130 mounted in journals supported by members 131 which latter are supported from the body-frame 1. Figure 6 illustrates the channeled construction of the rack-bar on its 85 outer side to receive a friction roller 132, and on the opposite side to receive the gear 130 and hold the latter on the cogs of the rack-bar. The bar is also channeled to receive flanges of vertical angle bar guides 133. 90 The gear wheel 130 is mounted on a shaft 135 which extends rearwardly to a suitable point above the platform 34, and mounted on this rear end of the shaft is a worm-wheel 136 that is driven by a worm 137 100 on a short counter shaft 138 having a hand wheel 139 mounted on its inner end for the manual lifting and lowering of the mold-board.

Fig. 5, also illustrates my improved 105 spring-mechanism which assists in lifting the mold-board off of the ground in one position of a lever 134, moving with the gear wheel 130, but which acts oppositely to pull the mold-board down when lever 134 is in 110 the lower arc of its circle of movement.

The lever 134 is shown in Fig. 5 in full lines in position of maximum elevation of the mold-board to assist in elevating the mold-board, by the action of a spring 135² 115 coiled around a fixed stud 136² and having an arm extension 137². A cable 138² has an end attached to the end of arm 137². It passes down and under a pulley 178, and thence up to the end of lever 134, to which it 120 is attached through a clevis 135². When, by manually rotating the gear-wheel 130 by the means described, in a direction contra clockwise to raise the mold-board, the pull of the spring on lever 134 has assisted in 125 raising it; and to lower the mold-board from the position of the gear and lever in the drawing, the spring counter-balances the weight of the blade until the lever 134 has passed the extension of a line drawn through 130

the axis of pulley 178 and gear wheel 130, when the direction of the pull of the spring is reversed and it acts to hold the mold-board in the ground with a yielding resistance which is very helpful. A series of holes 139' are provided in a suitable plate to receive a bent end of spring 135' at different adjustments therein of the spring to regulate the tension of the spring.

10 Attention is called to the fact that the front axle is a supporting member, only, and is not skewable as heretofore, to assist in steering the machine. But the front road wheels are mounted on studs which are connected by knuckles with the respective ends of the front axle, and are turned on said knuckles, in very much shorter circles than would obtain were the steering done by skewing the front axle in the old way, with 15 the advantage that more room is left for the adjustment and operation of the mold board without interfering contact with the front wheels.

Having thus described this invention what 20 I claim is:—

1. In a road making machine, a draft tongue, a draft bar to which the tongue is attached, a second draft-bar attached to the first one and extending rearwardly thereof, 25 the last draft bar being in two rearwardly diverging members, a pivot block extending transversely of the machine and attached to both of the diverging members intermediate their ends, a mold-board pivotally connected 30 with the pivot block, means to secure and retain a rotary adjustment of the mold-board on its pivot, and means in duplicate at the rear of the pivot transmitting the weight of 35 the machine to the two diverged members of the second draft-bar to hold the scraper blade in the ground.

2. In a road machine, a draft tongue, a draft bar to which the tongue is attached, a second draft-bar attached to the first one 40 and extending rearwardly thereof, the last

50 draft bar being in two rearwardly diverging members, a pivot block attached to both of the diverging members, a mold-board pivotally connected with the pivot block, means to secure and retain a rotary adjustment of the mold-board on its pivot, a yoke hinged to the rear ends of the two diverging draw bar members, said yoke being movable to swing the draw bar laterally of the machine to laterally adjust the working position of 55 the mold-board.

3. In a road making machine, a body-frame a mold-board below the frame, means comprising a rack and gear wheel for lowering and raising the mold-board, an arm 60 moving with the gear wheel, a spring and means cooperating with the spring and arm for utilizing the action of the spring to force the mold-board into the ground in one relation of said last means with the spring 65 and for lifting the mold-board in another relation of said last means with the spring.

4. In a road making machine, a body-frame a mold board below the frame, means comprising a rack and gear wheel for lowering and raising the mold-board, a spring 70 having an arm, a lever rocking with the gear wheel and means comprising a cable connecting the arm and lever to cause the spring to assist in raising the mold-board in one 75 position of the lever and to influence the mold-board in a reverse direction in another position of the lever.

5. In a road making machine, a body-frame, a mold-board, means comprising an 80 arm for lowering and raising the mold-board, a spring and means cooperating with the spring and arm for utilizing the action of the spring to force the mold-board into the ground in one relation of said last 85 means with the spring and for lifting the mold-board in another relation of said last means with the spring.

In testimony whereof I affix my signature.
JOHN M. LARSH.
